METHOD OF REMOVING DUST FROM
LEATHER

John G. Hollick, Beverly, Mass., assignor to
United Shoe Machinery Corporation, Flemington, N. J., a corporation of New Jersey

Application August 16, 1946, Serial No. 691,090

1 Claim. (Cl. 69—21)

1

This invention relates to a method of removing dust particles from the surface of tanned hides or skins, and is more specifically concerned with the freeing of leather surfaces from fine fibrous dust by means of a forced jet of gaseous fluid such as air.

Tanned hides or skins are usually subjected to a buffing operation to improve their appearance, after which the dust produced by that operation is removed from the leather surface. Such removal is for the purpose of presenting the leather in the best possible condition for subsequent finishing operations. If the dust were not removed, the resulting finish would be cloudy, streaked and unsightly.

Dust, and particularly that dust produced from buffing, is fine and fibrous and great difficulties are encountered in satisfactorily removing it from leather surfaces. The problems encountered are unique and quite unlike those involved in cleaning other types of sheet materials.

Heretofore it has been the practice to employ brushing machines to remove dust from leather. In using such machines, dust would momentarily be lifted by the brush from the leather surface. After such mechanical dislodgment, suction means would remove some of the dust suspended in the air. As the brushing action led to generation of static charges in the dust particles and also in the leather there has been a strong tendency for some of the dislodged dust to return to the leather despite the suction means. As a result, the finish and appearances of the work has suffered and the difficulties have not been avoided by the development and improvements in complicated brushing machines which are costly to manufacture and expensive to maintain.

It has now been discovered that dust may be removed from leather surfaces by an air jet to a degree not approached by the best brushing machines and that the capacity of the air handling equipment may be quite modest. The method is therefore economical and is aided in this direction by the discovery that the cleaning effect takes place substantially instantaneously and that the rate of feed of a work piece surface relative to a cleaning jet may be greatly increased as compared with the rate with which leather may be dusted in a conventional brushing machine. It has also been found that the dust dislodged by an air jet or blast may easily be controlled so that it will not return to the cleaned leather surface.

An object of the invention is to provide an improved method of removing dust from leather, the

latter being in the form of a hide or skin, which method is simple, efficient and economical.

In the accomplishment of the object in view and in accordance with the method herein illustrated, a forced jet of gaseous fluid such as air is directed against a narrow area of the surface of a spread-out leather work piece to be treated and at an angle such as to cause the jet to impinge against the surface and dislodge dust therefrom. All portions of the surface to be treated are progressively passed through the zone of impact of the jet. Thus not only is the dust most effectively dislodged from the leather under treatment but the dust laden air, after impingement, is forcibly directed away from the cleaned surface as an incident of the cleaning operation. The jet, before impingement, is given a limited width dimension of a few thousandths of an inch.

The invention will now be more particularly described by reference to the accompanying drawings and thereafter pointed out in the claim.

In the drawings,

Fig. 1 is a perspective view of one form of apparatus by means of which the method may be carried out; and

Fig. 2 is a view, in section, and drawn to a larger scale, showing the relation of the main operative parts of Fig. 1 in treating a leather work piece.

In the illustrated machine, a horizontal table or platform 10 is utilized upon which a leather work piece 12 may be supported and spread out and from which it may be progressively fed through the treatment zone or zone of impact. Bearing blocks 14 and 16 are rigidly attached to the opposite sides and at the end of the platform 10 and rotatively support the shaft 18 of an elongated rotary brush 20 having sufficient length to extend across and slightly beyond each side of the widest work piece the treatment of which is contemplated. A vertical bracket 22 is adjustably mounted and supported upon the bearing block 16 by suitable bolts 24 and 26. Each of these bolts passes through a vertical slot made in the bracket 22. A slot 28 is formed in the block 16 permitting angular adjustment of the bracket 22 about the bolt 24. The bearing block 14 supports a second vertical bracket 30 similar in all respects to the bracket 22 and likewise adjustably mounted. A horizontal bar 32 is supported on brackets 22 and 30 by flanges 34 and 36 bolted to the upper ends of the brackets 22 and 30.

As seen in Fig. 2, the bar 32 is formed with a recess 35 running longitudinally thereof and enclosed by two longitudinal plates 37 and 38. The

recess 35 does not extend the full length of the bar 32 but terminates adjacent each end thereof. The plate 38 is attached to the bar 32 by a multiplicity of screws 40 one of which is shown in Fig. 2. The longitudinal plate 37 extends from one longitudinal side of the bar 32 and almost abuts the plate 38 thereby leaving a slot 42 of slight width between its edge and the inner side of the plate 38. A multiplicity of cylindrical pins 44 are attached to the bar 32 by means of screws 46 (only one shown and that in Fig. 2) passing through the plate 37 into the bar 32. The cylindrical bars or pins 44 extend at an angle up over the platform or table 10, as shown in Fig. 2, and are smoothly contoured to guide the work into the bite between the plate 38 and the brush 20.

One end of the bar 32 is provided with piping connections 50 and a conduit 52, these devices serving as means for conducting gaseous fluid such as air under positive pressure from a source of supply to the recess 35. A pressure gage 54 is shown in Fig. 1. One end of the rotary brush shaft 18 has keyed thereto a pulley 60 through which power is applied to the machine by a belt 62 driven from motor means not shown.

In carrying out the method the pulley 60 and brush 20 are rotated in the direction shown by the arrows in Figs. 1 and 2 and air under pressure is permitted to enter the hose 52, piping connections 50, and the recess 35. The bar 32 is adjusted to a position such as shown in Fig. 2. The operator then places and spreads out a hide or skin 12 upon the table 10 and slides it in between the rods or pins 44 and the rotating brush 20. Regardless of the irregularities in the contours of the work piece the brush serves to progressively pull the work piece 12 by and in contact with the lower edge of the plate 38 and air, emanating in the form of a sheet from the slot 42 between the plates 37 and 38, impinges upon the surface of the spread-out work piece 12, dislodging dust therefrom. Before impingement, the thickness dimension of the jet is not excessively increased as the work piece is retained close up to the slot. As preferred and as disclosed in the apparatus shown, the dust-laden air then sweeps back over that portion of the work piece surface not yet cleaned and the treated portion 64 of the work piece surface emerges from the machine freed from dust.

The operator may hold back on a hide or skin and retard its passage if he so desires and, as a matter of fact, he may pull the work piece back toward him and then permit it to be treated again by the air jet. Usually one passage of a portion of a work piece past the slot or through the zone of impact is sufficient to remove the dust but it is obvious that the operator may, without removing the work from the machine, repeat the treatment of a given work piece any number of times, or he may prolong the treatment during a single passage by retarding the rate of feed.

A hood, for the removal of the dust-laden air, is not essential as the blast of air from the slot removes the dust such a distance that it does not return to the leather. It is preferable that the method be so carried out that the dust-laden air flies back over the leather portions yet to be fed by the slot. With the apparatus shown, the plate 38 and the bar 32 prevent dust-laden air from flying out over the dusted portion 64 of the leather. It is to be appreciated, however, that a hood may be used to insure that all dust is removed from the leather and will not return thereto.

An air pressure of from three to twelve pounds per square inch within the recess 35 has been found very satisfactory with a slot width of from .002" to .003". A pressure of three pounds per square inch performed work equivalent to that performed on the best brushing machines. The use of a twelve-pound pressure resulted in a far superior cleaning job.

It is preferred that the air be impinged against the work from a slot but it is clear that a number of closely arranged or staggered orifices of small thickness dimensions may be used and that these may constitute the cleaning jet. It is also permissible to reciprocate the slotted or perforated jet member to secure adequate coverage of the surface area to be treated. In some cases it may be well to increase the width dimension of the orifices or slots to as much as .015" or .020" although such increase will necessitate a great increase in the capacity of the blower and the power output.

Various velocities of feed for the work piece have been found satisfactory. The cleaning effect is substantially instantaneous for any given spot on a work piece despite the small width of the slot and cleaning jet as work-feed velocities of up to 325 feet per minute have been successfully used.

The specific apparatus disclosed includes the rotary brush 20 for feeding the work piece resiliently in contact with or closely adjacent to the plate 38. As the dust-laden air discharges, the Bernoulli effect is evident—potential energy is changed to kinetic energy and the pressure of the air within the jet is reduced and the leather is actually held (not repelled) adjacent to the slot 42 by the air jet. A rotary brush need not be used for feeding the work piece as that operation may obviously be carried out by hand or by a belt conveyor.

It may be seen from the above that the velocity of feed and the pressure of the fluid used are not critical conditions in so far as the invention is concerned. The impingement or impact angle of the jet (as measured with respect to the surface being treated and before impingement) should not be much lower than 40 degrees (although the 40-degree value is not critical) if the advantageous results are to be secured. The impingement angle of the jet has been found most satisfactory when approximately 90 degrees and the cleaning effect diminishes if the angle is adjusted or changed to approach zero.

It is preferred that the method be carried out as disclosed in Fig. 2 but it is not essential that the dust-laden air be discharged over the untreated portion of the work piece. The dust-laden air may be discharged in the other direction—i. e., over the treated work portion 64—and be separated therefrom by a thin plate or sheet and/or by causing the work piece to bend sharply away from the direction of movement of the dust-laden air.

Having described my invention, what I claim as new and desire to secure by Letters Patent of the United States is:

A method of removing dust from leather which comprises the spreading out of a work piece such as a hide or skin upon a support and passing said work piece progressively through a zone of treatment, and forcibly projecting a jet of air under a pressure of substantially three to twelve pounds per square inch directly against and also across the full width of the work piece to treat 75 the entire length of said work piece as it passes

through said zone, the impingement angle of the jet being above 40 degrees and the thickness dimension of said jet before impact being within the range of .002" to .020".
